(57) **CLAIM**

The ornamental design for a securing mechanism for a peripheral ultrasound device, as shown and described.

DESCRIPTION

FIG. 1 is a top perspective view of a securing mechanism for a peripheral ultrasound device showing my new design.

FIG. 2 is a bottom view thereof.

FIG. 3 is a top view thereof; and,

FIG. 4 is a side view thereof.

The broken lines in FIG. 4 are included for the purpose of illustrating unclaimed portions of the securing mechanism for a peripheral ultrasound device and form no part of the claimed design.

1 Claim, 4 Drawing Sheets
